(57) CLAIM

The ornamental design for an audio component face, as shown and described.

DESCRIPTION

FIG. 1 is an elevational view of an audio component face showing my new design;

FIG. 2 is a side elevational view of the left side thereof; and, FIG. 3 is a side elevational view of the right side thereof. The broken line showings of the indicia, knob, control buttons and other elements in the claimed area are for illustrative purposes only and form no part of the claimed design. The broken line showings of the feet and the remainder of the audio component are also for illustrative purposes only and form no part of the claimed design.
